DESIGN FOR AN ELECTRICAL WIRING BOX OR SIMILAR ARTICLE

Lee H. Peck, Chagrin Falls, Ohio, assignor to
Porcelain Products, Inc., Findlay, Ohio, a cor-
poration of Ohio

Application December 8, 1938, Serial No. 81,635

Term of patent 14 years

To all whom it may concern:

Be it known that I, Lee H. Peck, a citizen of the United States, residing at Chagrin Falls, in the county of Cuyahoga and State of Ohio, have invented a new, original, and ornamental Design for an Electrical Wiring Box or Similar Article, of which the following is a specification, reference being had to the accompanying drawing, forming part thereof.

In the drawing, Fig. 1 is a side elevational

view; Fig. 2 is a top plan view; and Fig. 3 is an end elevational view of an electrical wiring box showing my new design.

The dominant or characteristic features of my design are shown in the full black lines in the drawing.

I claim:

The ornamental design for an electrical wiring box or similar article, as shown and described.

LEE H. PECK.
